UNITED STATES PATENT OFFICE

2,587,506

FIRE ALARM

George L. Moreland, Peoria, Ill.

Application November 21, 1949, Serial No. 128,521

1 Claim. (Cl. 200—142)

1
The present invention relates to new and useful improvements in fire alarms, and more particularly to a circuit closer for fire alarm systems.

An important object of the invention is to provide a circuit closer for fire alarm systems which is normally held open by fusible means and wherein the circuit is closed by the melting of the fusible means when subjected to predetermined heat or flame.

A further object of the invention is to provide a circuit closer of this character including a case having fusible means at each end to hold the circuit in open position and whereby the circuit will be closed upon the melting of either fusible means.

A still further object is to provide a device of this character of simple and practical construction, which is efficient and reliable in operation, relatively inexpensive to manufacture, easy to install in a desired location in a building, and which is otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the circuit closer connected to an alarm in a self-contained fire alarm system;

Figure 2 is a vertical sectional view of the circuit closer;

Figure 3 is a similar view of the housing for the alarm; and

Figure 4 is a transverse sectional view taken on a line 4—4 of Figure 2.

Referring now to the drawing in detail, wherein, for the purpose of illustration, I have disclosed a preferred embodiment of the invention, the numeral 5 designates a cylindrical metal case having internal ribs 6 and 7 adjacent each end and against which metal washers or disks 8 and 9 are held by fusible disks 10 and 11 which may be composed of sealing wax or other suitable fusible material placed in a molten state in the respective ends of the case 5 to seal the ends thereof and to hold the washers 8 and 9 in position therein.

Each washer is formed with a central opening 12 and in which rods 13 and 14 are respectively positioned in spaced relation from the washers to project outwardly through the adjacent ends of case 5.

A terminal nut 15 is threaded on the outer end

of rod 13 for attaching a circuit wire 16 thereto and the outer end of rod 14 is provided with a head 17. A washer 18 is interposed between terminal nut 15 and fusible disk 10, and washer 18 and head 17 are held against the fusible disks 10 and 11 at the opposite ends of case 5 by a coil spring 19 connecting the inner ends of rods 13 and 14 to each other, and maintained under tension to exert an inward pulling force on the rod.

A second terminal 20 is welded or otherwise suitably secured to case 5 at its end adjacent terminal 15 and a circuit wire 21 is connected to terminal 20 by a nut 22 threaded thereon.

Circuit wires 16 and 21 are connected in a circuit with a dry cell battery 23 and an electric bell or other audible alarm 24, the battery and bell being enclosed in a housing 25.

In the operation of the device, the case 5 and housing 25 are placed in a suitable location in a building and the circuit wires 16 and 21 connect terminals 15 and 20 of the circuit closer with the battery and bell in a self-contained circuit. Should either end of case 5 be subjected to predetermined heat or flame sufficient to melt fusible disks 10 or 11, spring 19 will pull the rods 13 and 14 inwardly, whereby to either contact washer 18 with washer 8 or to contact head 17 with washer 9 and thus close the circuit and sound the alarm.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

A circuit closer comprising a metal case, a metal disk in each end of the case and having a central opening, a fixed terminal at one end of the case, a pair of conductor rods projecting outwardly through the openings in the disks at the ends of the case, spring means connected to the inner ends of the rods for moving the rods inwardly and providing a conductor between the rods, contacts at the outer ends of the rods, one of said rods constituting a second terminal,

and non-conductive fusible means sealing the ends of the case and positioned between the disks and the contacts to electrically separate the same from each other, and said fusible means also holding the rods in centrally spaced relation in the openings of the disks.

GEORGE L. MORELAND.
